UNITED STATES PATENT OFFICE

91,426

DESIGN FOR A COMB

Solom Goldberg, Louisville, Ky.

Application November 15, 1932. Serial No. 45,992

Term of patent 14 years

To all whom it may concern:

Be it known that I, SOLOM GOLDBERG, a citizen of the United States, residing at Louisville, in the county of Jefferson and State of Kentucky, have invented a new, original, and ornamental Design for Comb, of which the following is a specification, reference being had to the accompanying drawing, forming part thereof.

I claim:

The ornamental design for a comb as shown.

SOLOM GOLDBERG.
